DESIGN FOR A BRUSH

Abraham Lubkin, New York, N. Y.

Application April 6, 1942, Serial No. 106,474

Term of patent 3½ years

To all whom it may concern:

Be it known that I, Abraham Lubkin, a citizen of the United States, residing at New York, in the county of the Bronx and State of New York, have invented a new, original, and ornamental Design for a Brush, of which the following is a specification, reference being made to the accompanying drawing, forming a part thereof.

The figure in the drawing is an elevational view of a brush, showing my new design.

The characteristic feature of my design resides in a brush having the configuration shown.

I claim:

The ornamental design for a brush, substantially as shown and described.

ABRAHAM LUBKIN.
